JOHN G. ANDERSON

BY

J. L. Rivers ATTORNEY

UNITED STATES PATENT OFFICE.

JOHN G. ANDERSON, OF PYSH, WASHINGTON.

BOOM-STICK AND METHOD OF PREPARING SAME.

1,335,416.

Specification of Letters Patent. Patented Mar. 30, 1920.

Application filed November 18, 1918. Serial No. 263,057.

To all whom it may concern:

Be it known that I, JOHN G. ANDERSON, a citizen of the United States, residing at Pysh, in the county of Clallam and State 5 of Washington, have invented a new and useful Boom-Stick and Method of Preparing Same.

My invention relates to a new method of preparing logs for booming and towing purposes, which consists in adjusting them to a boring mechanism while the logs are floating in water so that a vertical bore is made near the ends thereof and through the entire diameter of same, together with a counterbore of considerably larger diameter, adapted to receive and securely hold a chain and toggle, for holding a series of logs together for purposes above mentioned. Heretofore logs have been prepared for these purposes by slow, laborious hand labor, and among the objects of my invention is to achieve the desired result in a newer, quicker and better way, at a saving of labor and material.

I attain these objects by the method illustrated in the accompanying drawings, in which—

Figure 1 is a front elevation of a machine adapted to make the bore and counterbore, in connection with a plan view of an end of a log prepared under my method.

Fig. 2 is a side plan of the ends of two logs prepared under my new method, and fastened together with chain and toggles.

Fig. 3, a top plan view of a log provided with a bore, and a counterbore.

Fig. 4, a side elevation of a boring mechanism and log float and cross-section of a log in position for boring.

Similar numerals refer to similar parts throughout the several views.

Various devices can be used for making the bore and counterbore, but a device that I have found effective is illustrated in Fig. 1. It consists of a framework to which the drill 2, of comparatively large diameter and the drill 3 of smaller diameter are suitably mounted, said drills adapted to revolve vertically by gearing. 4 and 4' represent the levers which coöperate with gearing to lower or raise the drills into or out of operative position. 5, 6 and 7 mechanism which co-
operates with said levers. 8 represents the

chain by which the floating log is held in position for boring. 9, 9' and 10 and 10' 55 gearing to which power is transmitted by chains. 11, a float on which the boring mechanism is mounted. 13, log in position for boring, being held in place by chain and also the framework of the float. 14, 60 counterbore. 15, smaller bore. 16, chain connecting toggles. 17 and 17' toggles connected to chain, and said toggles seated in the counterbores. 18, platform upon which an operator stands for positioning the log 65 and operating levers.

In preparing a log under this method, the log is floated underneath a projecting side of the float until one end is properly positioned under the large drill 2, the log being 70 held in place by the chain 8, the drill 2 then making the bore 14 as shown. The depth of this bore as shown in the illustration is about one-third the thickness of the log, but this depth and its location from the end of the log varies according to the size of the log to be prepared, the operator always having in view that there must be enough wood structure to give sufficient strength for the purpose intended, the depth 75 of the large bore in a small log being considerably less than that in a large log. The log is then floated down to the smaller drill 3, it being held in position for boring by the chain 8, when the smaller bore 15 is made. 80 The log being floated on through the channel in the float the other end is prepared in the same way, the result being a log provided with a bore and a counterbore near each end, as shown in Fig. 3. Fig. 2 shows the ends of 85 two logs prepared in this new way, the large bores 14 and 14' affording seats for the toggles 17 and 17', the toggles being connected by the chain 16 passing through the smaller bores. As is known to anyone skilled in the 90 art, the old way of connecting a series of logs together for booming or towing purposes, consisted in chopping out with an ax a recess on the top and bottom portions of a log near the ends, or sloping off the ends 95 of a log with an ax until the thickness of the log at the ends was reduced to about 16 inches, then boring holes therethrough adapted to connect logs thus prepared, with toggles and chains. This method, as will 100 be perceived, is very slow and laborious, and

the chopping process wasted a great deal of timber; by it, two men can ordinarily prepare but two or three logs a day. Under this new method of preparing the ends, and 5 with a six horse power engine applied to the boring means, two men can make forty to 50 sticks a day. Under the old method the material chopped away was wasted. The new method saves timber, and produces a 10 stronger boomstick. In the old style boomsticks, in order to save chopping, the holes for the toggles are placed close to the ends, and as the projecting piece which holds the chain and toggle is ordinarily only about 15 16 inches thick, the boom sticks would frequently break out at the ends, a serious matter in towing or booming. By the new method the holes can be placed back from the ends any distance desired, without any 20 extra trouble or labor. Regulating this distance by the size of the log, the boom sticks are prepared so it is practically impossible for the chain and toggles to break out the wood structure. For instance, if the large 25 bore is 16 inches back from the end, there is a length of 16 inches of the timber to withstand the strain of the toggles and chain, on each end. This strain in towing and booming of logs is sometimes very great.

I intend to make the apparatus described 30 herein, the subject of another application.

I claim:

1. The method of connecting boom sticks end to end with chains of equal length having end toggles, which consists in forming a 35 transverse bore partially through each stick, forming in axial alinement with said first bores, second bores of greater diameter than said first bores and extending said second bores partially through the sticks so as to 40 form, in conjunction with said first bores, shoulders, and passing the chains through said first bores and seating said toggles upon said shoulders.

2. The combination of a plurality of boom 45 sticks and chains for connecting them, said boom sticks being provided at adjacent ends with transverse bores extending therethrough and with other bores of greater diameter than said first bores to form in 50 conjunction with said first bores shoulders, said chains extending through said first bores and carrying toggles at their ends seated upon said shoulders, said second bores being of varying depth whereby boom sticks 55 of different diameters are connected by chains of a uniform length.

JOHN G. ANDERSON.
